Patented May 9, 1922.

FIG 4. 6

Newton S. Hillyard, INVENTOR
BY
George W. Hinton, ATTORNEY

UNITED STATES PATENT OFFICE.

NEWTON S. HILLYARD, OF ST. JOSEPH, MISSOURI.

FLEXED-BLOTTER HOLDER.

1,415,642.

Specification of Letters Patent.

Patented May 9, 1922.

Application filed July 20, 1920. Serial No. 397,584.

To all whom it may concern:

Be it known that I, NEWTON S. HILLYARD, a citizen of the United States, residing at St. Joseph, in the county of Buchanan and State of Missouri, have invented certain new and useful Improvements in Flexed-Blotter Holders, of which the following is a specification, reference being had therein to the accompanying drawing.

10 My invention relates to improvements in flexed-blotter holders, and the objects of my improvements are, first; to provide a blotter holder of this class, in which either one, or a plurality of sheets of blotting paper can 15 easily and quickly be detachably secured in flexed form, thereby providing a tightly stretched curved blotting surface into which the fluid portion of written ink is absorbed, without appreciably spreading the latter, 20 second; to so construct a blotter holder that a practically unobscured advertising space, of ample proportions is exposed to view at all times, third; to so construct a blotter holder of this class, that the ends of a plurality of sheets of blotting paper are neatly 25 housed and obscured from view and to so form the parts that the hand of the user of said blotter holder, can not be injured by sudden contact therewith, fourth; to so arrange and construct the parts of a blotter holder that said holder can be instantly 30 grasped and used, thereby avoiding much loss of time, which is experienced in hunting for and picking up the ordinary flat blotter, 35 fifth; to so construct said blotter holder that it shall be extremely neat in appearance, light of weight, and substantial, be cheap in cost of manufacture and occupy the minimum amount of space when packed for storage or shipment.

I attain these objects by the devices illustrated in the accompanying drawings, in which:

Figure 1 is a longitudinal section, cut vertically through the center of all the parts. Fig. 2 is a top view of the blotter holder. Fig. 3 is a bottom view of the blotter holder, showing the perforations through the blotting paper. Fig. 4 is a longitudinal edge view of the elastic metal back sheet, as it appears when removed from the holder.

Referring to Fig. 1, since the two holders for holding the ends of the hereinafter described sheets are alike in construction and operation, but one holder is described.

Holder 1 is of practically segmental form, transversely, and is preferably made of sheet metal, of sufficient thickness to be substantial. The two edges of said holder 1, are projected downward. One of the edges of 60 said holder is return bent, inwardly upon itself, forming the rigid, rounded pressing edge 2, which does not abrade the herein-after described back sheet. The outer edge of said holder is bent inward and upward, 65 forming the holding edge 3. The center of said holder is securely connected with the center of the holder 4, by the rod 5, with the holding edges 3 of said holders arranged as shown in Fig. 1.

The ends of said rod are passed through apertures formed through said holders respectively, and are secured therein, by solder, which is applied to said ends and to the adjacent inner surfaces of said holders. 70 While said rod is secured as shown and described it is evident that the same could be connected with said holders, in any good substantial manner, known to the metal workers' art, without departing from the 75 spirit of my invention, which I reserve the right to do.

Referring to Figs. 1 and 4, the back sheet 6 is preferably formed of elastic sheet metal, which when released from the described 80 holders 1 and 4, straightens to the shape, seen by reason of its elasticity. The outer surface of said back sheet (see Fig. 2), is adapted to receive subject matter, such as advertisements and the like, printed thereon, or otherwise applied thereto. Or the same may be applied to both surfaces of said sheet, for insuring the advertiser, that his advertisement will be exposed at all times.

The blotting paper 7 is cut in sheets, 90 which are the same width as said back sheet, but are sufficiently longer to permit their ends to be folded back upon said back sheet, which is done, as seen in Fig. 1. Perforations 8 are formed through the end portions 100 of said sheets of blotting paper (see Fig. 3,) in such position, that they are close to the holding edges 3 of the holders.

In operation, the user of the blotter holder places a plurality of sheets of blotting 105 paper 7 against the back sheet 6, and bends the ends of the sheets of blotting paper upon the back of said back sheet, as seen in Fig. 1, after which he inserts one end of the thus formed pile of sheets into one of the hold- 110

ers. He thereafter flexes said pile of sheets and inserts the other end thereof into the other holder and releases said pile of sheets.

The flexed end portion of the back sheet 6, which extends into the holder 1, is ful-crumped on the pressing edge 2, thereby increasing the pressure of said back sheet at its extremity, which increased pressure is exerted on the end portion of the pile of 10 sheets of blotting paper 7, firmly pressing the latter against the holding edge 3.

While in this position, as seen in Fig. 1, the ends of said pile of sheets are abutted against the inner surfaces of the holders 15 1 and 4, which hold said ends against longitudinal movement. The edges 3 of said holders hold the end portions of said pile of sheets against movement downward, out of said holders. The edges 2 hold the end 20 portions of said sheets, snugly against each other, and press thereon during the operation of the described blotter holder.

In using the described blotter holder and the blotting paper held thereby, the user of 25 the same grasps the bar 5 and by it and its connected parts, gently presses the back sheet 6 downward, thereby pressing a portion of the surface of the exposed sheet of blotting paper 7, upon the ink to be thereby 30 absorbed. He thereafter rocks the described holder back or forth, or in both directions, without sliding said blotting paper upon the writing, thereby absorbing the liquid portions of said ink.

35 After said exposed sheet becomes so saturated with ink, that a clean sheet is desired, he places the edge of an edge tool or the end of any pointed instrument, between said saturated sheet and the adjacent sheet 40 of blotting paper, and thereby tears said saturated sheet, along one of the lines of perforations 8, until said sheet is thereby sufficiently released to be grasped by the hand. He then grasps the thus freed portion of said sheet of blotting paper and 45 tears it along the lines of perforations 8, removing said saturated sheet from the holder and exposing a clean sheet of blotting paper 7.

50 Said operator repeats the previously described operations of removing a saturated sheet of blotting paper, until the entire plu-

rality of said sheets is thus used, after which 55 he removes the back sheet 6 and repeats the operations of replenishing the holder with new blotting paper.

In actual practice, it is frequently the case, that the conventional flat blotting paper is beneath other flat sheets of paper and lies flat upon the desk or table, which cause the loss of a considerable amount of time and patience in finding and picking it up. In evenly pressing it upon the ink, to be 60 thereby absorbed, it frequently happens that the passage of the hand thereover, produces a wave in said flat blotting paper, in advance of the hand. Farther movement of the hand as it flattens said wave, causes the 70 blotting paper thereahead to creep over the ink, thereby causing unsightly blots in the writing.

My handle 5 being above the surface of the desk is seldom obscured from view, is 75 easily and instantly grasped, and the flexed blotting paper is thereby quickly applied to the ink to be absorbed, without any of the previously described injury to the writing and in the minimum amount of time. 80

Having fully described my invention, what I claim as new and desire to secure by Letters Patent, is:

A sheet holder transversely of segmental form; a pressing edge formed of one of the longitudinal edge portions of said holder return bent upon itself; a holding edge on the other longitudinal edge of said holder said holding edge being formed of a portion of said holder bent at an incline inward 90 and upward with a space between said holding edge and said pressing edge for insertion therebetween of one of the transverse edges of an elastic flexed back sheet and of a flexed plurality of perforated sheets 95 of blotting paper; another sheet holder of the same construction for similarly holding the opposite ends of said sheets; and a rod the ends of which are secured in the center of one of the sides of said holders respectively at a right angle thereto with the pressing edges of said holders beneath the respective ends of said rod. 100

In testimony whereof I affix my signature.

NEWTON S. HILLYARD.
